CLAIM

The ornamental design for a manifold housing for a medical waste collection device, as shown and described.

DESCRIPTION

FIG. 1 is a rear, top, left side perspective view of a manifold housing for a medical waste collection device; FIG. 2 is another rear, top, left side perspective view thereof; FIG. 3 is a front, bottom, right side perspective view thereof; FIG. 4 is a left side perspective view thereof; FIG. 5 is a front, bottom perspective view thereof; FIG. 6 is a left side view thereof; FIG. 7 is a right side view thereof; FIG. 8 is a rear view thereof; FIG. 9 is a front view thereof; FIG. 10 is a top view thereof; and, FIG. 11 is a bottom view thereof.

The dotted lines in the drawings depict portions of a manifold housing for a medical waste collection device that form no part of the claimed design. The dash dot lines immediately adjacent to the claimed areas in the views represent the boundaries of the claimed design and does not exist in the reality of the manifold housing. None of the broken lines form any part of the claimed design.
